AUTOMATIC GAUGE REGULATOR FOR
GRINDING AND POLISHING MACHINES

Wallace K. Lowe, Syracuse, N. Y., assignor to Crucible Steel Company of America, New York, N. Y., a corporation of New Jersey

Application February 12, 1951, Serial No. 210,561

12 Claims. (Cl. 51—165)

1

This invention pertains to gauge adjusting and automatic gauge regulating apparatus for grinding and polishing machines, and the like, which apparatus is arranged to provide for either manual or automatic adjustment and regulation of the gauge or thickness of the stock being ground or polished.

Although the invention is applicable to grinding and polishing machines in general, in which elongated stock is surface ground or polished by feeding the same past the one or more motor driven abrading elements, it is primarily intended for use in conjunction with centerless grinding and polishing machines, particularly of the type described in my copending application Serial No. 199,410, filed December 6, 1950, of which this application is a continuation-in-part.

The invention comprises, in its essentials, a reversibly energizable screw-down motor for adjusting the motor driven abrading element toward and away from the stock surface to be ground or polished. This screw-down motor may be reversibly energized, either manually by means of push-button switches, or automatically by means of a regulator relay having a pair of magnetically coupled and opposed energizing coils, for actuating and controllably positioning, a pivotally mounted contact arm, which is deflectable from a median or neutral position, between the oppositely disposed fixed contacts, respectively, to energize the screw-down motor in one direction of rotation or the reverse.

The abrading element motor or motors is or are energized over a power supply circuit to which the magnetically opposed relay coils are current and voltage coupled respectively, over a pair of coupling circuits individual thereto. The current coupling circuit contains a rheostat for adjusting the relay contact arm to its neutral position, midway between its fixed contacts, for any given load current supplied to the abrading element motor or motors, during the grinding operation. This rheostat is of the rotary type, the rotary arm of which is mounted on the shaft of a reversible-drive, rheostat control motor.

The rheostat control motor may be energized in one direction of rotation or the reverse, either manually by means of push-button switches, or automatically by means of a second regulator relay, similar to that which controls the screw-down motor, in that it is provided with a pair of magnetically coupled and opposed energizing coils, controlling a movable contact arm which pivots between oppositely disposed fixed contacts, respectively, to energize the rheostat motor

2

in opposite directions of rotation. This rheostat control relay is in turn controlled by a gauging element, which latter continuously gauges the stock being ground, and, in such manner, that as long as the stock is being ground to the preselected gauge for which the regulator is set, the contact arm of the rheostat control relay will remain in its neutral position, midway between its fixed contacts, but will respond to variations in the measured gauge, to deflect its contact arm in one direction or the reverse against the corresponding fixed contacts, in turn to so adjust the rheostat as correspondingly to actuate the screw-down motor control relay. The screw-down motor is thus energized in such direction of rotation and to the extent required, to restore the grinding to the preselected gauge. A switch actuated relay circuit is provided to arrange the gauge regulator for either manual or automatic control.

20 In operation, the regulator is initially arranged for manual adjustment, and the grinding or polishing machine is started up in conventional fashion, to feed the elongated stock past the abrading element, the motor driving the latter being also switched on. The screw-down motor is thereupon adjusted by means of the push-button contacts until the abrading element is grinding the stock to the desired or preselected gauge, as determined, for example, by manual gauging. Thereupon the rheostat is adjusted by appropriate push-button actuation of its control motor, until the contact arm of the screw-down motor control relay is positioned at neutral, i. e., midway between its fixed contacts. The system as thus 25 adjusted is now ready for automatic regulation, and is cut over to automatic control, by means of the above mentioned switch actuated relay circuit provided for this purpose.

With the gauge regulator thus operating under automatic control, the contact arms of the screw-down motor and rheostat control relays will remain in their neutral positions as long as the stock is being ground to the preselected gauge. Should, however, the gauge increase or decrease 30 with respect to the preselected value, the gauging element will actuate the rheostat control relay contact arm against the appropriate fixed contact for compensatively adjusting the rheostat, the adjustment of which will correspondingly actuate the screw-down motor or control relay, in turn, compensatively to energize the screw-down motor until the preselected gauge is restored.

In addition to the basic components of the regulator circuit above described, it also embodies various other refinements as will be ex-

plained below in the detailed description having reference to the accompanying drawings, wherein the regulator is described as applied to a centerless grinder of the type covered by the aforesaid copending application.

In the drawings:

Figure 1 is a side elevation of the centerless grinder to which the present invention is applied by way of illustrative example, but without limitation thereto; while Figure 2 is a section thereof taken at 2—2 of Fig. 1.

Figure 3 is an end view, partly in section and with parts broken away, of one of the two grinding heads of the Fig. 1 construction; while Figure 4 is a side elevation, partly in section and with parts broken away, of this same grinding head. Figures 5 and 6 are sectional views thereof at 5—5 and 6—6 respectively of Fig. 3, while Figure 7 is a further section at 7—7 of Fig. 6.

Figure 8 is a circuit diagram of the gauge regulator of the present invention as applied to the centerless grinder of Figs. 1-7 inc.

Referring to Fig. 1, the centerless grinder to which the invention is applied comprises in general, a feed and straightening unit 20, a grinding and/or polishing unit 21, a control unit 22, and a reeling or coiling unit 23, the grinder being adapted for grinding long lengths of rod or wire stock such as is conveniently handled in reel or coil form.

To this end an unwinding reel or frame is provided at 24 for reception of a coil of stock to be ground, and from which it is unwound and fed into the apparatus. The wire stock is indicated at 25 and is directed first to a pinch roll unit indicated generally at 26 and which includes a pair of peripherally grooved rolls 27 and 28 between which the wire stock passes and which feeds the stock into the wire straightening unit 29. One or both of said pinch rolls preferably are power driven by a motor 30 through the intermediary of a reduction gear 31, the latter being connected to said rolls as by a sprocket chain 32.

The grinding and polishing unit 21 comprises a main supporting shaft 33 which is journaled for rotation in suitable bearings 34 and 35. Shaft 33 is rotated by an electric motor 36, Fig. 2, which is operatively connected thereto by means of a worm and wheel reduction unit, 37 and by a sprocket chain 38 which engages suitable sprocket wheels 39 and 40 respectively secured to the shaft 33 and to an output shaft of said reduction unit 37.

Secured to opposite extremities of shaft 33 are grinding heads 41 and 42 which may be respectively employed for "rough" and "finish" grinds upon the stock 25. The grinding heads 41 and 42 are each completely enclosed by protective housings 43 and 44, respectively.

The motor 36 is mounted upon a main pedestal 45 which in turn supports a journal pedestal 46 upon which the journals 34 and 35 are mounted.

Referring now to Figs. 3, 4 and 5, the main supporting shaft 33 rests in a suitable sleeve bearing as of Babbitt metal 35c, the latter comprising a part of said bearing 35. At the right-hand extremity of the main supporting shaft 33 (Fig. 4) the grinding head 41 is located. This grinding head includes disc-like supporting head 47 which is rigidly secured to the shaft 33 for rotation therewith. The main supporting shaft 33 has formed therein an axial passage 33a through which the wire stock 25 is fed. As

shown in Fig. 4, the wire stock is directed toward the center of the supporting head 47 and hence toward the axial passage in the main supporting shaft 33, the latter two elements being concentric. The wire stock 25 moves from right to left as viewed in Fig. 4.

The grinding head 41 is provided with a pair of grinding wheels 48 and 49 which are mounted, as in Fig. 4, on opposite sides of the axis of the main supporting shaft 33 and hence similarly with respect to the supporting head 47, said wheels being in so-called face-to-face relationship, the faces of which are slightly canted with respect to each other. Individual motors are provided for rotating the grinding wheels 48 and 49, as at 50 and 51, respectively. The rotors of these motors are coaxial with and rigidly secured to their respective grinding wheels 48 and 49. The grinding wheels 48 and 49 are thus arranged to grind the wire stock 25 upon flat faces 48a and 49a (Figs. 4 and 5) rather than upon their peripheral edges 48b and 49b.

The grinding wheels 48 and 49 are mounted for axial movement in such a manner that they contact diametrically opposite surface portions of the stock 25 being ground. Also the grinding faces 48a and 49a, by virtue of the canting of the axes of the grinding wheels, are set at an acute angle to the direction of stock feed and to the axis of the main supporting shaft 33.

Said motors 50 and 51 are mounted in the manner illustrated in Fig. 5 wherein the mounting for motor 50 is shown in detail. This mounting comprises a cylindrical outer housing 52 which surrounds a cylindrical inner housing 53, the latter enclosing a stator 54 and a rotor 55 which is mounted upon a rotor shaft 56. The latter mounts the grinding wheel 48. The inner housing 53 is adapted for axial sliding movement in the cylindrical outer housing 52 but is restrained from angular movement therein by virtue of the key 57 which is secured to the housing 53 and engages a suitable groove in the housing 52.

The canting of the axes of the grinding wheel 48 is accomplished by securing the outer housing 52 to the supporting head 47 by means of a wedge-shaped member 58 which may be formed integral with a mounting plate generally indicated at 59 which may form a part of the outer housing 52. It is preferable for the mounting plate 59 with its wedge-shaped portion 58 to engage a suitable recess formed in the supporting head 47 and to be secured therein in a well-known manner, as by bolts. The mounting for motor 51 is analogous to that of motor 50. Thus each grinding wheel and its associated driving motor is mounted as a unit and is axially adjustable toward and away from the stock being ground in a manner to be explained more fully hereinafter.

A coolant or a lubricant solution to facilitate the grinding is supplied to the stock at the region of abrasion by means of a supply conduit 60 having branches 61 and 62 respectively directed to the grinding heads 41 and 42. In Fig. 4 there is shown in detail a nozzle 63 for directing such solution onto the region of the stock undergoing grinding and also onto the stock prior to the time it is abraded by the grinding wheels. The stock 25 passes through a suitable passageway in a ring 66 of the nozzle 65, thence through the passage in the nozzle 64, and thence to the grinding wheels. The grinding solution thus is directed onto all sides of the wire stock 25 prior

to the time that it emerges from the nozzle 64.

In order to retain the solution for recirculation and reuse, a bowl member or a bowl-like retaining vessel, having an aperture formed in the center of the bottom thereof for the passage of the wire, is provided as at 67 and may be secured to the main supporting shaft 33 by any suitable means. Said aperture in the bottom of the bowl member 67 is shown as at 68, the latter being in register with the axial passage 33a formed in the shaft 33. Suitable hand controlled valves, as at 74, 75, are interposed respectively in the conduits 61 and 62 for controlling the volume of such solution directed upon the work-piece.

Referring again to Fig. 5, the grinding wheel 48 is mounted upon a metal plate 76 by means of suitable nuts 77 and bolts 78. The mounting plate 76 is secured to a bed plate or motor disc 79 by bolts, one of which is shown at 80. The disc 79 is formed with a central bore for the reception of the outer extremity of the motor shaft 56, such extremity being indicated at 56a. A shoulder 56b is formed on said shaft to the left of the portion 56a, as viewed in Fig. 5, upon which said plate 79 rests and is held thereagainst by means of a cap plate 81 and bolts 82. The motor shaft 56 is provided with roller bearings 83 for absorbing radial thrusts, said bearings 83 being at the righthand extremity of the shaft, as viewed in Fig. 5, and thus near that extremity of the shaft 56 which supports the grinding wheel 48.

The grinding wheel 48, in order to engage the wire stock 25, may be urged to the right (Fig. 5) and consequently a suitable thrust bearing as at 84 is provided for communicating thrust in such direction to the shaft 56 and hence to said grinding wheel. For aiding in disengaging the grinding wheel from the wire stock or in moving same to the left (Fig. 5), a suitable bearing is provided for communicating thrust to the left from the housing to the shaft 56, such bearing being provided at 85. The inner ring of bearing 85 may, if desired, be rigidly held to the shaft 56 by means, for example, of an end plug 86. However, the operative interconnection between said bearing and the housing of the motor for communicating thrust to the left may include a bearing plate as at 87 which surrounds the shaft 56 and by suitable shoulders at 88 contacts the outer ring of said bearing, said bearing plate 87 being operatively associated with the housing 53 by means of yielding members comprising springs 89 which surround arms 90, the latter being connected to the bearing plate 87.

The stationary outer race or ring of the bearing 83 is embraced by a flanged bearing plate 91. The latter is secured to an annular or ring-shaped member 92 by any suitable fastening means as at 93. Member 92 is rigidly secured, as by welding, to the inner housing 53. The inner face of the ring 92 is provided with a stepped surface 92a for the reception of a bearing plate 94, the latter being removable for disassembly purposes upon the unfastening of the means 93 and the removal of the bearing plate 91. The bearing plate 94 provides along the inner margin thereof a shoulder for communicating thrust to one of the rings of the bearing 84, said thrust being to the right (Fig. 5) and being communicated to the shaft 56 via the other ring of bearing 84 and via a flanged sleeve 95, the latter engaging the shoulder 56b via the inner race of the bearing 83.

A portion of the outer cylindrical surface of the inner housing 53 is threaded, as at 53a, and such threaded portion is embraced by an annular shaped gear 96 having a toothed periphery and a threaded inner surface, the latter being designed for threaded engagement with said threaded portion 53a. It is clear, if suitable means, comprising for example the key 57, are provided for preventing angular movement of the inner housing 53 and for preventing axial movement of the gear 96, that angular movement of the latter will be translated into axial movement of the housing 53 and hence the grinding wheel 48 which is axially movable therewith. The means for restraining said gear from axial movement comprise, in the form shown, a pair of flanges 97 and 98 which are situated fixedly adjacent opposite faces of the gear 96. The flange 97 preferably is formed integral with the outer housing 52 and surrounds the latter. The flange 98 is rigidly secured relative to the flange 97 by any suitable means whereby there is no relative movement therebetween. Suitable bearings are interposed between the flanges 97 and 98 and the gear 96. Thus, a bearing ring 99 is interposed between the flange 97 and the gear 96 and a ball bearing as at 100 is interposed between the flange 98 and said gear, the latter bearing having been found desirable in order to assist in urging the grinding wheel to the right as viewed in Fig. 5 and against the wire stock.

Referring to Fig. 3, the annular gear 96 is shown in connection with the motor 50 and an analogous gear 101 is shown in connection with motor 51, the latter being operatively associated with this motor in a manner analogous to that of gear 96. Means are provided for simultaneously shifting said gears 96, 101 angularly in order to move the grinding wheels 48, 49 axially in opposite directions. Said means comprise a common adjusting or screw-down motor 102 (Figs. 3, 6 and 7) which is securely mounted upon the supporting head 47, as shown in Fig. 6, wherein motor 102 is supported in a suitable aperture near the margin of said supporting head 47. The motor 102 transmits torque simultaneously to said gears 96 and 101 by an operative interconnection consisting of the following: A worm 103 secured to a shaft 104 of the motor 102 is in engagement with a worm wheel 105 which is keyed to a shaft 106. To the latter shaft there is also keyed a pinion gear 107 which meshes with a pinion gear of substantially larger diameter as at 108, the latter in turn being in keyed engagement with a supporting shaft 109. The elements 103-108 thus constitute a reduction gear train for very substantially reducing the R. P. M. of the motor 102. Because of the above-described canting of the axes of the motors 50 and 51 and the grinding wheels 48 and 49, it is necessary to employ universal couplings 110 and 111 for respectively interconnecting the shaft 109 with the remaining portions of the operative interconnection to said gears 96 and 101. The universal coupling 110 communicates the torque of shaft 109 to a shaft 112 mounted in a suitable bracket 113 and having secured thereto a chain sprocket gear 114. The latter, by means of a chain belt 115, interconnects the gear 114 to a chain-sprocket 116, the latter in turn being secured to a shaft 117 upon which there is also secured a pinion gear 118 which meshes with said gear 96.

The coupling 111 for the gear 101 is operatively

interconnected to the latter by analogous means. It is understood that the threading upon the inner housings of the motors 50 and 51 is such that actuation of the motor 102 will cause the grinding wheels to move axially and concurrently in opposite directions.

The slip ring structures for communicating electrical energy to the three motors of each grinding head are shown at 119, 120 of Fig. 1.

In operation, the grinding wheels are separated by a sufficient distance, by appropriate actuation of the screw-down motors as explained below, to permit free passage of the wire stock 25 while the latter is being threaded through the machine whereupon the motor 36 is started for rotating the grinding wheels planetarily around the wire stock, at which time the screw-down motors, such as 102, may be actuated to move the grinding wheels, such as 48, 49, to a point where they engage the wire stock, the motors of the grinding head 41 being adjusted for a "rough cut" and the motors for the head 42 being adjusted for a "finish cut."

Due to the high reducing action of the gear train and the related operative interconnection between the adjusting motor, such as 102, and the inner housing of the motors 50, 51, it is possible to control the movement of the grinding wheels with substantial accuracy because a single revolution of the motor 102 provides a very minute axial movement of said grinding wheels.

Reference will now be had to Fig. 8 for a description of the automatic regulator circuit for adjusting and maintaining the stock being ground at the gauge desired. Motor pairs 175, 176 and 177, 178 are the grinding motors that drive the opposed pairs of abrading discs, corresponding to motors 50, 51, Figs. 3 and 4, motors 175, 176 being mounted on the left grinding head and motors 177, 178 on the right grinding head as viewed in Fig. 1. Motors 179, 180 are the screw-down motors of the left and right grinding heads, corresponding to motor 102, Figs. 3, 6 and 7, for adjusting the spacing between the grinding wheels, such as 48, 49, Fig. 3, in accordance with the required gauge to which the stock is to be ground. These are all three phase induction motors, energized from three phase supply lines, such as 181, 182, knife switches 183, 184, being provided for disconnecting the power.

During the grinding operation, the grinding motors 175 to 178 inc. are normally running continuously while the screw-down motors 179, 180, are normally at rest. To this end motors 175 to 178 inc. are connected directly to the power supply lines 181, 182, through conventional push-button actuated start-stop connections omitted for simplicity of illustration. Each of the screw-down motors, 179, 180, is connected, on two of its phases, to supply lines 181, 182, through front contacts and armatures of a pair of control relays 185, 186 and 187, 188, respectively, and in the manner shown at 189 and 190. These connections are such, as shown, that when relays 185 and 187 are energized, motors 179 and 180 are connected to the supply lines in phase rotation such, that the screw-down motors adjust the pairs of grinding motors and grinding discs toward each other on the grinding heads, thus to decrease the gauge of the stock being ground, this adjustment being effected as described above in connection with Figs. 3 to 7 inc. On the other hand when relays 186 and 188 are energized, the phase connections to the spacing motors 179,

180, are interchanged, as compared to the operation of relays 185 and 187, whereby these screw-down motors are energized to rotate in the opposite direction to that first described and thus back the pairs of grinding motors and discs away from the stock thus to increase the gauge thereof.

Relay pairs 185, 186 and 187, 188 are energized respectively from direct current supply lines 191, 192 and 191a, 192a, being bridged thereacross in series with normally open and normally closed contacts of the pairs of push-buttons 193 and 194, 195 and 196, 197 and 198, and 199 and 200, the pairs 193 and 196, 194 and 195, 192 and 199, and 197 and 200 being ganged as shown. Thus when push-button 193 is depressed relay 185 is energized, and similarly for relays 186, 187, 188 upon depression of push-buttons 195, 198, 200. Owing to the ganging arrangements only one relay of each pair may be energized at a time. Thus by manipulation of these push-buttons the grinding motors and discs on each grinding head may be displaced toward or away from the stock, manually to adjust the gauge being ground, as desired. For indicating the load on each grinding motor, ammeters are coupled to a supply line of each through current transformers, as at 201, 202.

For providing automatic gauging, the screw-down contact relays 185, 186, are placed under control of a regulating relay or "regulator" 203; and similarly the screw-down control relays 187, 188, are placed under control of a regulator 204. These regulators are of a conventional construction obtainable from the General Electric Company under the designation "electrode regulator." Each regulator 203, 204, is provided with a pair of magnetically coupled coils 206, 207 and 208, 209, wound on a common armature as shown, but in opposed relation, such that equal currents flowing in the same direction therein, respectively, will produce equal and annuling fluxes, thus to position a pivoted contact arm 212 or 213, midway between its left and right fixed contacts. Conversely an increase or decrease in current flow through one coil 206 or 208 of each meter, over that of the other coil 207 or 209, will swing the associated contact arm 212 or 213, against its left or right hand contacts as the case may be.

The energizing circuits for the control relays 185, 186, and 187, 188, are traced from the positive power leads 191, 191a, through a front contact and armature of a relay 211, as explained below and thence, for control relays 185 and 187, through the left hand fixed contact and contact arms, respectively, of regulators 203, 204, and for control relays 186, 188, through the right hand fixed contact and contact arms, respectively, of the regulators 203, 204, all circuits traced extending thence to the negative power lead 191, either directly or over connections 192a. It will thus be seen, assuming relay 211 to be energized to close through the power leads 191a, that so long as the regulator contact arms 212, 213, remain in their median or neutral positions midway between their left and right fixed contacts, that all of the screw-down control relays will remain deenergized. On the other hand if the regulator contact arms 212, 213, swing against their left hand fixed contacts, the "screw-in" relays 185, 187, will be energized, in turn to energize the screw-down motors 179, 180, to advance the grinding head motors 175, 176 toward each other, and the same for motors 177, 178. Conversely if the regulator contact arms swing against their right hand fixed contacts, the control relays 186, 188, will be energized to back

the grinding head motors of each pair away from each other, as above explained.

Coil 206 of regulator 203, is energized in proportion to the current supplied to the grinder motors 175, 176, over a circuit 212 which includes a current transformer 213 coupled to one of the supply lines 181. The output of current transformer 213 is fed to a shunt rheostat 214, of the rotary type, and thence through a step-up transformer 215 to the input terminals of a full wave rectifier 216, such as a dry rectifier of the selenium type, the output terminals of which are connected to winding 206 of regulator 203.

A rectified current proportional to the voltage supplied to the grinder motors 175, 176, is supplied to the coil 207 of regulator 203, over a circuit 217 which includes a step-down transformer 218, a rotary type potentiometer 219, a full wave rectifier 220, the output terminals of which are connected across the fixed arm of a potentiometer 221, the variable arm of which is tapped across coil 207, as at 222.

The connections to coils 206 and 207 are such that the magnetic flux produced by the resulting rectified current flow in coil 206, opposes the magnetic flux produced by the resulting rectified current flow in coil 207. As above stated the current flow in coil 206 is proportional to the load current taken by the grinding head motors 175, 176, while the current flow in coil 207 is proportional to the voltage impressed on these motors. As explained below, the contact arm 212 of regulator 203, is initially and manually adjusted to its median or neutral position by means of the rheostat 214, at the load current taken by the grinder motors 175, 176, when grinding the stock to the desired or preselected gauge.

The circuits for regulator 204 are similar to those above described for regulator 203, and hence require no detailed description. Thus coils 208, 209 are current and voltage coupled respectively to the supply line 182 through full wave rectifier circuits 224 and 225, similar to 212 and 217. Circuit 224 includes a shunt rheostat 228, similar to 214 of circuit 212. The rotary arms of these rheostats are respectively mounted on shafts 229, 230, of reversible motors 231, 232, which are reversibly energizable through field coils 233, 234 and 235, 236 of these motors, respectively. Motor 231 may be manually controlled to rotate in one direction or the reverse by means of push-buttons 237, 238, through the contacts of which the motor field windings 233, 234, in series with the motor armature, are respectively connectible to an alternating current supply line 239. The field windings 235, 236 of motor 232 in series with the armature thereof, are similarly connectible to the supply line 239, through the contacts of push-buttons 240, 241 and over connections 242, 243, to the supply line 239.

In addition to the manual adjustments of rheostats 214, 228 effected in the manner above described, they may be automatically adjusted in accordance with the preselected gauge to which the stock passing through the grinding apparatus is to be ground. This is accomplished by means of the equipment shown in the lower right portion of the drawing and including a regulator 244, having a pair of magnetically coupled energizing coils 245, 246, poled in opposed relation. These coils act differentially on a pivotally mounted needle 247, adapted to swing between left and right pairs of contacts 248, 249, thus concurrently to energize the rheostat motors 231, 232, through their lower

or upper field windings 234, 236 or 233, 235, depending on whether the regulator needle swings left or right from a median or zero position.

These energizing circuits are traced from one side of the supply line 239 through contacts 270 of an interrupter 271, as described below, thence over connection 272 to the needle of regulator 247 and through the meter contacts to the motor windings, returning thence through the motor connection to the opposite side of the supply line.

The regulator coils 245, 246, are respectively connected to a pair of similar photo-cells or tubes 250, 251, by means of the obvious connections 252 shown, which include a common or center tap return path. The photo-cells 250, 251, are energized from a light source 252, through lens systems 253, 254, which direct beams 255, 256, onto the photo-cells 250, 251, respectively. These beams are focussed in front of the cells, as at 260, 261. Just beyond the focus point for beam 256, there is interposed in the path of the beam a wire or rod 262 of precisely the gauge to which the stock passing through the grinder is to be ground, the stock itself being fed, as at 263, through the path of beam 255, at a position corresponding to that of the standard gauging element 262 in beam 256. Thus the standard gauging element 262 and the stock 263 to be gauged cast greatly magnified shadows on photo-cells 251 and 250 respectively.

If the stock 263 being gauged is of precisely the same diameter as the standard gauging element 262, the shadows cast on photo-cells 250, 251, will be equal, producing equal and opposed direct currents in the meter coils 245, 246, in consequence of which the regulator needle 247 will remain in the neutral or median position shown. If on the other hand the stock 263 being ground becomes over gauge or under gauge, the shadow area cast on photo-cell 250 will increase or decrease with respect to that of cell 251. This will produce a net current flow through the regulator coils 245, 246, the direction of which will depend on the direction of unbalance, thus to swing the regulator needle left or right as the case may be against contacts 248 or 249. The rheostat motors 231, 232 will accordingly be energized to rotate clockwise or the reverse, thus compensatively to adjust the rheostats 214 and 228. This in turn will correspondingly vary the current flow through the current measuring coils 206, 208, of regulators 203, 204, the contact arms of which will in turn swing left or right from the median position, and against the associated left or right contacts of each. Assuming relay 211 to be energized, the motor control relays 185 and 187 or 186 and 188 will thus be energized, in turn to energize the screw-down motors 179, 180, in one direction of rotation or the reverse, compensatively to adjust the grinding motors 175, 176 and 177, 178 either away from or toward the stock being ground, as the case may be, until the gauge of the stock 263 being ground has been readjusted to that of the gauging standard 262, whereupon the contact arms of regulators 203, 204, and 244, will swing back to their median or zero positions, thus to deenergize the rheostat and screw-down motors 231, 232 and 179, 180.

For arranging the control circuit for either manual or automatic gauging control, as desired, relay 211 connected over conductors 267, and thence through a step-down transformer 268 and switch 269 to the A. C. supply line 239. Accordingly when switch 269 is open, relay 211 is de-energized, thus to open the supply line 191a,

thereby preventing the regulators 203, 204 from energizing any of the spacing motor relays 185-188 inc., which are thus energizable only by the manual actuation of the push-buttons 193-200. On the other hand when switch 269 is closed to energize relay 211 and connect the supply line 191a to the regulator contacts, the circuit is arranged for automatic regulation.

In order to prevent over-travel of the rheostat adjusting motors 231, 232, the aforesaid interrupter 271 is bridged across the supply line 239, in series with its interrupt contacts 270, through which contacts current is also supplied, or stated, to the rheostat motors 231, 232 via connection 272. Thus the rheostat motors are energized step-by-step fashion to effect the gauging balance without over-travel.

In the operation of the gauging control circuit, the stock to be centerless ground, is threaded through the centerless grinder in the manner illustrated in Fig. 1. The pedestal motor 36, Fig. 2, is switched on, by conventional circuits above mentioned, and also the grinder motors 175 to 178, Fig. 19, are energized, as illustrated schematically by closing switches 183, 194. The screw-down motors 179, 180, are thereupon manually adjusted by means of the push-buttons 193-200 inc., until the desired reduction of the ground stock is being obtained, this being effected by manual gauging of the stock as it passes through the apparatus. During this adjustment the indicating ammeters 201, 202 are referred to for an indication of load balance. When the proper gauge is attained, the knife switch 272 in supply line 239 is closed, and the regulators 203 and 204 manually adjusted to their median or zero positions, by means of the push-buttons 237 to 241 inc., controlling the rheostat motors 231, 232. Thereupon switch 269 is closed thus cutting the system over to automatic regulation as above described.

The ensuing operation of the automatic regulating circuits is as follows. Assume that the machine is running and that the load adjusting rheostats 214, 228, have been set for the desired load in the manner above explained, and as will be indicated by the volt meters 273, 274, connected in shunt respectively to the current measuring coils 206, 208 of the regulators 203, 204, the contact arms 212, 213 of which will now be in their median or zero positions. As the load on the machine increases, the voltage produced by the current transformers 213, 213a increases. This voltage is stepped up by transformers 215, 215a, and rectified by the full wave rectifiers 216, 216a. The resulting rectified voltages increasingly energize the current measuring coils 206, 208, of the regulating relays 203, 204, so that the resulting magnetic fluxes produced by these coils, overbalances the fluxes produced by the opposing coils 207, 208 respectively. This causes the contact arms 212, 213 to swing against their right hand fixed contacts, thus in turn to energize the control relays 186, 188, in turn to energize the screw-down motors 179, 180, in such direction of rotation as to cause the grinding motors 175, 176 and 177, 178, to back away from the stock being ground, until the load on the grinder head motors is restored to its initial value. Should thereafter the load on the machine decrease, the voltage across the regulator coils 206, 208, will correspondingly decrease, and the resulting decrease in magnetic fluxes produced thereby, will cause the overbalancing fluxes of coils 207, 209 respectively to swing the

regulator contact arms 212, 213, against their left hand fixed contacts respectively, thus to energize the control relays 185, 187, in turn to energize the screw-down motors 179, 180, in the reverse direction to that aforesaid, to now advance the grinder head motors toward each other, until a condition of balance is again restored.

The fact that the voltage energized coils 207, 209 of the regulators are connected in opposed relation respectively to their associated current energized coils 206, 208, causes the regulator contact arms 212, 213 to "jog" as the desired load is approached. This prevents overtravel of the screw-down mechanism. Also as stated, the interrupter contacts 270, are interposed in the energizing circuits for the rheostat motors 231, 242, when under control of the automatic regulating relay 244, in order to allow current to flow therethrough only for predetermined intervals, thus additionally lessening the possibility of overtravel of the rheostat motors, and corresponding over- or under-adjustment of the load adjusting rheostats 214, 228.

The Fig. 8 circuit arrangement actually embodies two automatic sizing control circuits for each set of grinder head motors, namely that of regulator 203, for the grinder head motors 175, 176, and that of regulator 204 for the grinder head motors 177, 178, on which is superimposed the overall control circuit of regulator 244, applicable to both sets of grinder head motors. The circuit of regulator 244 responds more quickly to changes in the gauge of the stock being ground, than do the regulators of circuits 203, and 204, so that at no time can regulators 203 and 204 take over the automatic regulation control, unless the necessary response is called for by regulator 244. On the other hand, since the stock is being ground at two different points, namely at one point by the grinding motors 175, 176, and at another point by the grinding motors 177, 178, it becomes necessary to anticipate or determine which of the two grinding units may require adjustment, or perhaps both, at any given instant. To this end the balanced circuit arrangement due to the opposing coils 206, 207 and 208, 209 for regulators 203 and 204, provide individual regulation for the two grinding heads, which are extremely sensitive to changes of current in the respective sets of grinding head motors, viz. 175, 176 on the one hand, as compared to 177, 178 on the other. For retarding any undue fluctuations of current in the current measuring coils 206, 208, such as would not warrant a change in adjustment of the grinding heads, choke coils 230, 230a are bridged across the transformers 215, 215a respectively which choke coils thereby act as "scrubbers."

What is claimed is:

1. A gauge adjusting and automatic regulating apparatus for grinding and polishing machines having a motor driven abrading element for surface grinding elongated stock, said apparatus comprising: means including a reversible screw-down motor for relatively displacing said abrading element toward and away from said stock; a pair of switching means for selectively energizing said motor in one direction of rotation and the reverse for positioning said abrading element to grind said stock to a preselected gauge; and means for thereafter automatically controlling the positioning of said abrading element to maintain said gauge, said means including a relay having a contact arm deflectable in one direc-

tion between fixed contacts, to actuate one said switching means and deflectable in the opposite direction to actuate the said second switching means; a gauging element for continuously gauging said stock; and means responsive to said gauging element for oppositely energizing said relay in response to variations in the gauge of said stock above and below said preselected gauge and in such direction as to compensate for said variations through compensatory adjustments of said screw-down motor.

2. A gauge adjusting and automatic regulating apparatus for grinding and polishing machines having a motor driven abrading element for surface grinding elongated stock, said apparatus comprising: means including a reversible screw-down motor for relatively displacing said abrading element toward and away from said stock; a pair of switching means for selectively energizing said motor in one direction of rotation and the reverse to position said abrading element to grind said stock to a preselected gauge; and means thereafter automatically controlling the positioning of said abrading element to maintain said gauge, said means including a relay having a contact arm deflectable in one direction between fixed contacts to actuate one said switching means and deflectable in the opposite direction to actuate the second said switching means; means for adjusting said relay to a neutral position of deflection according to said preselected gauge; a gauging element for continuously gauging said stock; and means responsive to said gauging element for oppositely energizing said relay in response to variations in the gauge of said stock above and below said preselected gauge, and in such direction as to compensate for said variations through compensatory adjustments of said screw-down motor.

3. A gauge adjusting and automatic regulating apparatus for grinding and polishing machines having a motor driven abrading element for surface grinding elongated stock, said apparatus comprising: means including a reversible screw-down motor for relatively displacing said abrading element toward and away from said stock; a pair of switching means for selectively energizing said motor in one direction of rotation and the reverse to position said abrading element to grinding said stock to a preselected gauge; and means for thereafter automatically controlling the positioning of said abrading element to maintain said gauge, said means including a relay having a contact arm deflectable in one direction to actuate one said switching means and deflectable in the opposite direction to actuate the second said switching means, and having a pair of magnetically coupled and opposed energizing coils for said contact arm; a power supply circuit for energizing said abrading element motor, and circuits current and voltage coupling the same to said relay coils, respectively, and means for adjusting currents in said coils to equality for adjusting said contact arm to a neutral position of deflection according to said preselected gauge; whereby said relay thereafter responds to variations in current supplied to said motor compensatively to actuate said relay and thereby adjust the positioning of said abrading element through compensative adjustments of said screw-down motor.

4. A gauge adjusting and automatic regulating apparatus for grinding and polishing machines, comprising the combination with means for feeding elongated stock and a motor driven

abrading element for surface grinding said stock, of means including a reversible screw-down motor for adjusting said abrading element against and away from said stock surface; means for adjusting said screw-down motor to position said abrading element to grind said stock to a preselected gauge, and means for automatically maintaining said gauge, including a first relay having a contact arm deflectable between oppositely disposed fixed contacts for oppositely energizing said screw-down motor, and having a pair of magnetically coupled and opposed energizing coils for said contact arms, a power supply circuit for energizing said abrading element motor, and circuits current and voltage coupling the same to said relay coil respectively, means for adjusting the current in said coils to a condition of balanced opposition at the load current value of said abrading element motor when grinding to said preselected gauge thus to adjust said relay contact arm to neutral at said load current value, whereby subsequent variation of said load current above and below said value, oppositely deflects said relay contact arm compensatively to adjust said screw-down motor until said value is restored.

5. In a surface grinding and polishing machine having means for feeding elongated stock and a motor driven abrading element for surface grinding the same, a gauge adjusting and automatic regulating apparatus comprising: a reversible screw-down motor for adjusting said abrading element against and away from said stock surface, switching means for adjusting said screw-down motor to position said abrading element to grind said stock to a preselected gauge, and means for automatically maintaining said gauge including a first relay having a contact arm pivoting between oppositely disposed fixed contacts for oppositely energizing said screw-down motor, and having a pair of magnetically coupled and opposed energizing coils for said contact arm, a power supply circuit for energizing said abrading element motor, and circuits current and voltage coupling the same to said relay coils respectively, a rheostat in said current coupling circuit and a reversible motor for adjusting the same, means for adjusting said rheostat motor in turn to adjust said first relay to a neutral position between said contacts at the load on said abrading element motor corresponding to said preselected gauge, and means for automatically maintaining said adjustment including a second relay like the first, having a contact arm pivoting between fixed contacts for oppositely energizing said rheostat motor, a gauging element for continuously gauging said stock, and means responsive to variations of said gauging element above and below said preselected gauge for oppositely energizing said second relay and thereby by said first relay, thereby compensatively to adjust said screw-down motor and abrading element.

6. A gauge adjusting and automatic regulating apparatus for grinding and polishing machines having a motor driven abrading element for surface grinding elongated stock, said apparatus comprising: means including a reversible screw-down motor for relatively displacing said abrading element toward and away from said stock; a pair of switching means for selectively energizing said motor in one direction of rotation and the reverse; means for manually actuating said switching means to position said abrading element to grind said stock to a preselected gauge;

and means for thereafter automatically controlling the positioning of said abrading element to maintain said gauge, said means including a regulator having a pivotally mounted contact arm deflectable in one direction to actuate one said switching means and deflectable in the opposite direction to actuate the second said switching means, a gauging element for continuously gauging said stock, and means responsive to said gauging element for selectively deflecting said regulator contact arm in response to variations in the gauge of said stock and in such direction as to compensate for said variations through compensatory actuation of said screw-down motor.

7. A gauge adjusting and automatic regulating apparatus for grinding and polishing machines having a motor driven abrading element for surface grinding elongated stock, said apparatus comprising: means including a reversible screw-down motor for relatively displacing said abrading element toward and away from said stock; a pair of switching means for selectively energizing said motor in one direction of rotation and the reverse; means for manually actuating said switching means to position said abrading element to grind said stock to a preselected gauge; and means for thereafter automatically controlling the positioning of said abrading element to maintain said gauge, said means including a regulator having a pivotally mounted contact arm deflectable in one direction to actuate one said switching means and deflectable in the opposite direction to actuate the second said switching means, means for adjusting said regulator to a neutral position of deflection according to said preselected gauge, a gauging element for continuously gauging said stock, and means responsive to said gauging element for deflecting said regulator contact arm in response to variations in the gauge of said stock, and in such direction as to compensate for said variations through compensatory actuation of said screw-down motor.

8. A gauge adjusting and automatic regulating apparatus for grinding and polishing machines having a motor driven abrading element for surface grinding elongated stock, said apparatus comprising: means including a reversible screw-down motor for relatively displacing said abrading element toward and away from said stock; a pair of switching means for selectively energizing said motor in one direction of rotation and the reverse; means for manually actuating said switching means to position said abrading element to grind said stock to a preselected gauge; and means for thereafter automatically controlling the positioning of said abrading element to maintain said gauge, said means including a regulating relay having a pair of magnetically coupled energizing coils and a pivotally mounted contact arm deflectable thereby in one direction to actuate one said switching means and deflectable in the opposite direction to actuate the second said switching means, a power supply circuit for energizing said abrading element motor, and means current and voltage coupling said regulator coils thereto, respectively, and means for adjusting said regulator relay to a neutral position of deflection according to said preselected gauge; whereby said regulator thereafter responds to variations in current supplied to said motor, compensatively to adjust the positioning of said abrading element through compensative actuation of said screw-down motor.

9. A gauge adjusting and automatic regulating apparatus for grinding and polishing machines, comprising the combination with means for feeding elongated stock and a motor driven abrading element for surface grinding said stock, of means including a reversible screw-down motor for adjusting said abrading element against and away from said stock surface; manual switching means for adjusting said screw-down motor to a preselected gauge, and means for automatically maintaining said gauge, including a first regulator relay having a contact arm deflectable between oppositely disposed contacts for oppositely energizing said screw-down motor and a pair of magnetically coupled energizing coils for controlling the positioning of said contact arm, a power supply circuit for energizing said abrading element motor and circuits current and voltage coupling said regulator coils thereon, respectively, a rheostat in said current coupling circuit and a reversible motor for adjusting the same; manual switching means for reversibly energizing said rheostat motor, and means including a second regulator relay like the first and having a contact arm deflectable between oppositely disposed fixed contacts for automatically and reversibly energizing said rheostat motor, a gauging element for continuously gauging said stock, and means responsive to said gauging element for oppositely energizing said second regulator relay in response to variations of said stock gauge above and below said preselected value, thereby correspondingly to energize said first regulator for compensatively adjusting said screw-down motor.
10. In a surface grinding and polishing machine having means for feeding elongated stock and a motor driven abrading element for surface grinding the same, a gauge adjusting and automatic regulating apparatus comprising: a reversible screw-down motor for adjusting said abrading element against and away from said stock surface, switching means for manually adjusting said screw-down motor for a preselected gauge, and means for automatically maintaining said gauge including a first regulator relay having a contact arm pivoting between fixed contacts for oppositely energizing said screw-down motor, and having a pair of magnetically coupled energizing coils for controlling said contact arm, a power supply circuit for energizing said abrading element motor, and current and voltage circuits coupling said power supply circuit to said coils, respectively, a rheostat in said current coupling circuit and a reversible motor for adjusting the same, means for manually adjusting said rheostat motor for adjusting said first regulator contact arm to a neutral position between said fixed contacts at the load on said abrading element motor corresponding to said preselected gauge, and means for automatically adjusting said rheostat motor including a second regulator relay like the first, having a contact arm pivoting between fixed contacts for oppositely energizing said motor, a gauging element for continuously gauging said stock, and means responsive to variations of said gauging element above and below said preselected gauge for oppositely energizing said second regulator and thereby said first regulator, thereby compensatively to adjust said screw-down motor and abrading element.
11. In a machine for surface grinding elongated stock: means for feeding said stock and a motor driven abrading element for surface

grinding the same, a reversible screw-down motor for adjusting said abrading element toward and away from said stock surface, switching means for manually adjusting said screw-down motor to a preselected gauge, and means for automatically maintaining said gauge including a first regulator relay having a contact arm pivoting between fixed contacts for oppositely energizing said screw-down motor, and having a pair of magnetically coupling energizing coils for controllably positioning said contact arm, an energizing circuit for said abrading element motor, and circuits current and voltage coupling the same to said regulator coils, respectively, said current coupling circuit including a rheostat for adjusting the current flow in the regulator coil coupled thereto, a reversible motor for adjusting said rheostat, switching means for manually adjusting said rheostat motor, and means including a second regulator relay like the first having a contact arm pivoting between fixed contacts for automatically adjusting said rheostat motor, a gauging element for continuously gauging said stock, and means responsive to variations in said gauging element for oppositely energizing said second regulator, and thereby said first regulator, compensatively to adjust said screw-down motor and abrading element, a control circuit including a manually actuated switch for converting said machine from manual to automatic gauging, an energizing circuit for said rheostat motor, including said contacts of the manual and automatic switching means therefor, and an interrupter interposed in said circuit.

12. A gauge adjusting and regulating apparatus for centerless grinders and the like having at least one motor driven abrading element for surface grinding elongated stock, said apparatus comprising: means including a reversible screw-down motor for relatively displacing said abrading element toward and away from said stock; a pair of relay switching means for selectively energizing said screw-down motor in one direction of rotation and the reverse; means for manually actuating said switching means to position said abrading element to grind said stock to a preselected gauge; and means automatical-

ly controlling the positioning of said element to maintain said gauge, said means including a first regulator relay having a contact arm pivotally deflectable between oppositely disposed fixed contacts for actuating said switching means, respectively, and having a pair of magnetically coupled energizing coils for controllably positioning said contact arm, means for energizing said regulator coils, respectively, in accordance with the current and voltage supplied to said abrading element motor, said means including said regulator coils and a rheostat for adjusting the current supplied to one said coil in accordance with the power required to grind said preselected gauge; a reversible rheostat motor for adjusting said rheostat, a pair of manually actuated switching means for energizing said rheostat motor in opposite directions of rotation, respectively, and means for automatically energizing said rheostat motor to compensate for variations in gauge of the stock being ground, said means including a second regulator relay like the first and connections therefrom to said rheostat motor for oppositely energizing the same in response to opposite deflections of said second regulator, a gauging element for continuously gauging said stock, and means responsive to said gauging element for deflecting said second regulator in response to variations in the gauge of said stock and in such direction as to compensate for said variations, said second regulator in turn correspondingly actuating said first regulator compensatively to adjust said screw-down motor and abrading element.
